US0D1034955S

(12) **United States Design Patent** (10) **Patent No.:** **US D1,034,955 S**
(45) **Date of Patent:** **** Jul. 9, 2024**

(54) **NASAL SPRAY DEVICE**

(71) Applicant: **APTAR FRANCE SAS**, Le Neubourg (FR)

(72) Inventor: **Ludovic Petit**, Vitot (FR)

(**) Term: **15 Years**

(21) Appl. No.: **35/515,292**

(22) Filed: **Sep. 5, 2022**

(80) **Hague Agreement Data**

Int. Filing Date: **Sep. 5, 2022**

Int. Reg. No.: **DM/223629**

Int. Reg. Date: **Sep. 5, 2022**

Int. Reg. Pub. Date: **Oct. 7, 2022**

(30) **Foreign Application Priority Data**

(57) **CLAIM**

The ornamental design for a nasal spray device, as shown and described.

DESCRIPTION

1. Nasal spray device

1.1 : Perspective

1.2 : Front

1.3 : Back

1.4 : Right

1.5 : Left

1.6 : Top

1.7 : Bottom

The broken lines depict portions of the nasal spray device that form no part of the claimed design.

The article of manufacture to which the ornamental design has been applied is a nasal spray device that is used in the pharmaceutical field.

1 Claim, 7 Drawing Sheets
